CLAIMThe ornamental design for an abrasive disc for dental
prosthesis, as shown and described.**DESCRIPTION**Fig. 1.1 is a front perspective view of an abrasive disc for
dental prosthesis;

Fig. 1.2 is a back perspective view thereof;

Fig. 1.3 is a front view thereof;

Fig. 1.4 is a back view thereof;

Fig. 1.5 is a left side view thereof;

Fig. 1.6 is a right side view thereof;

Fig. 1.7 is a top view thereof; and

Fig. 1.8 is a bottom view thereof.

(Continued)

The broken lines shown in the drawings indicate contours of the abrasive disc.
